UNITED STATES PATENT OFFICE

RALPH R. PITTMAN AND CARROLL H. WALSH, OF PINE BLUFF, ARKANSAS

AUTOMATIC FUSE-CHANGER

Application filed April 2, 1932. Serial No. 602,666.

This invention relates generally to protective devices for electrical circuits, and particularly to fusible devices used for preventing the passage of excess currents through said circuits, and has for its principal object the provision of means for automatically restoring the continuity of a circuit interrupted by the operation of a fuse through the replacement of the blown fuse by an auxiliary fuse.

Another object of the invention resides in the novel arrangement of parts whereby the time required for the restoration of service over the circuit interrupted by a blown fuse is reduced to a minimum. In connection with the operation of overhead distribution lines, it is now well known that a large percentage of the total faults are caused by lightning flash-overs of such a character that the parts flashed are not permanently damaged. Such faults cause a short interruption to service, and certain synchronous equipment is stopped. It is an object of this invention to provide means for reducing the time of the interruption to a value of the order of one-tenth of a second, which is a much shorter time interval than that provided by any other means known to us.

A further object of this invention is to provide a simple, inexpensive and effective device for the purpose above described.

With the above and other objects in view which will appear as the description proceeds, our invention resides in the novel construction, combination and arrangement of parts as hereinafter described and more particularly defined by the appended claims, it being understood that such changes as come within the scope of the claims may be made in the embodiment herein disclosed.

In the drawings, Figure 1 is a front elevational view of the device.

Figure 2 is a side elevational view of the device.

Figure 3 is a side elevational view of a tripping plunger assembly, shown partly in section.

Figure 4 is an end view of a tripping plunger assembly.

Figure 5 is a front elevational view of a tripping plunger assembly.

Figure 6 is a front elevational view of the latching assembly.

Figure 7 is an end view of the latching assembly.

Figure 8 is a side elevational view of the latching assembly.

Figure 9 is a front elevational view of the hook member for supporting the fusible contact members.

Figure 10 is a plan view of the hook member for supporting the fusible contact members.

Figure 11 is a plan view of the top fuse terminal and contact shown with the cap removed.

Figure 12 is a fragmentary elevational view of the top fuse terminal and contact, shown with the cap removed.

Figure 13 is a side elevational view of the device following its operation, and with one fusible contact member manually pulled down preparatory to removing same for refusing.

As shown by the assembly views illustrated by Figures 1, 2, and 13, the fuse-changer consists generally of three upstanding fuses, supported by a pair of insulators. The central fusible contact member 11 is normally in the circuit, and the lateral fusible contact members 10 and 12 are supported in an auxiliary position external to the circuit. The sequence of operation of the particular embodiment here shown is as follows: Upon the melting of the fusible element in contact member 11, contact member 10 moves to a position to close the circuit opened by the melting of the fusible element in contact member 11. Following this action, upon the melting of the fusible element in contact member 10, the contact member 12 moves to the circuit-closing position.

Referring now more in detail to the assembly views illustrated by Figures 1, 2 and 13, insulators 77 and 78 are rigidly attached to a supporting metallic base 79 by means of the cap screws 80.

Suitably secured to insulator 77 by means of the cap screws 81 is a metallic plate 68.

having longitudinally extending arms and a laterally extending arcuate portion adapted to substantially align with the metallic cap of insulator 78. On each longitudinally extending arm of plate 68 is mounted by means of cap screws 82 the bent metallic member 67, consisting of a substantially square section of metal rod folded at the center portion to form a pair of parallel bars in spaced relation, the main portion of the folded section substantially normal to plate 68. One end of the folded section of the metallic member 67 is bent at right angles to the main portion to provide a surface for attaching the member 67 to the plate 68, and the other end is provided with an upwardly disposed end portion for providing a resilient mounting for the control contact clip 86, as by the cap screws 84.

20 The J-shaped metal strap 89 provides a terminal for a line wire at one end, and supports the contact clip 73 at the other end.

The metallic plate 47 is supported, as by the bolt 85, on insulator 78, and is shown more in detail in Figures 6, 7 and 8. Two pairs of extending portions of the plate 47 are bent to form short cylindrical extensions from the plate, each pair being adapted for forming one-half of a hinged joint at the lower side of the plate. At the other side of the plate are mounted the U-shaped tripping rods 53 and 44, the tripping rod 53 being supported on the front of the plate 47 by the bearing 52, and the tripping rod 44 being supported on the rear of the plate 47 by the bearings 46.

For cooperating with the hinged portion of plate 47 is provided the two bent members 50 and 65 having a bent cylindrical portion for forming a hinge with the extended portion of plate 47, and in addition a pair of downwardly and forwardly extending hooks. The pins 72, together with the extended portions of the plate 47 and the bent members 50 and 65 provide a means for hingedly fixing the members to the plate 47. The U-shaped springs 48 and 88 having, by means of the cap screws 83, one extremity of the U fixed to the plate 47 and the other extremity to the bent member 50, provides means for biasing the bent members 50 and 65 respectively in a clockwise direction away from the plate 47. The contact clips 49 and 63 are rigidly attached by some suitable means, as welding, to the bent members 50 and 65 respectively.

The plate 47, in addition to hingedly supporting the contact clips 49 and 63 as above described, also rigidly supports the central lower contact clip 62, and the flat extended bar 70, the latter providing a load terminal for the device.

65 The central contact member 11 comprises the tube of insulating material 28, to each end of which is attached in some suitable man-

ner, as by means of complementary threads, the upper contact 35 and the lower contact 29, adapted for cooperating respectively with the upper central contact clip 73 and the lower central contact clip 62. Adjacent the upper contact 35 are provided the hooks 75, biased by the spring 33 in a direction to latch the top of the contact member 11 in the cooperating contact 73. The eye 32 is adapted for operation by the usual type of insulated switch hook, and arranged so that a downward movement of the eye 32 raises the hooks 75, thus unlocking the contact member, for convenience in removing the contact member 11 from the support. The top of the contact member is provided with a cap 34 for entirely closing the top of the contact member 11, and in addition as shown more in detail in Figures 11 and 12, by means of cooperating threads, and a slot 27 and the button 26 on the fusible element 25, provide means for tightly engaging the fusible element with the top contact 35.

A slotted metallic tube 57 shown in detail in Figures 3, 4 and 5 is rigidly attached to the rear of each of the lower contacts 29 and 37 by means of a flattened side of the tube 57, and screws extending through the respective lower contact 29 or 37 into the flattened side of the respective tube 57. A plunger 55, also a metallic tube having an outside diameter somewhat less than the inside diameter of its slotted tube 57 extends therethrough, forming the inner tube 55 concentric with the outer tube 57, and centered therein by the bushing 56. The inner tube 55 is adapted for reciprocatory movement within the outer tube 57 and is guided and limited in its reciprocations by means of a pair of oppositely extending pins 59, the latter engaging the sides of the slot in the outer tube 57. The spring 58 is adapted to engage the pins 59, and in this manner the inner tube 55 is biased in an upward direction.

To better illustrate the assembly, Figures 3 and 4 have been drawn showing the spring 58 deformed following the downward movement of the inner tube 55.

A metallic cap 61 is provided for engaging the cooperating threads at the top of the inner tube 55 which is used in connection with the contact member 11 (see Fig. 13), and for the further purpose of rigidly clamping the button 23 to the upper end of the inner tube 55, in this manner forming a lower terminal for the fusible element 25. The flexible conductor 60 is provided for carrying the current from the fusible element 25 to the outer tube 57. A metal yoke 45 is rigidly fixed to the inner tube 55 which is used in connection with the contact member 10 for the purpose of laterally transferring the movement of the respective inner tube 55. The inner tube 55, with the related members above described, forms a

plunger biased in an upward direction by the spring 58, and arranged to be moved in a downward direction by means of tension on the fusible element 25 against the bias of the 5 spring 58.

To insert a fusible element in contact member 11, the caps 34 and 61 are removed and the extended end of the fusible element 25, together with the top button 26 is first 10 urged downwardly through the plunger 55 until the lower button 23 contacts the upper end of the plunger 55. The cap 61 is then replaced in position on the upper end of the plunger 55. The extended end of the fusible 15 element 25 is then urged in an upward direction through the insulating tube 28 until the end of the fusible element appears at the top of the tube. At this point, the plunger 55 is manually urged in a direction against the 20 bias of the spring 58, this movement permitting the upper button 26 to be moved laterally and held in place by the slot 27. The cap 34 is then replaced. Upon the completion 25 of this procedure, the fusible element is subjected to a tension due to the spring 58, and the plunger 55 is biased to move in an upward direction upon the parting of fusible element 25.

Assuming that contact member 11 has been 30 properly fused as above described, and inserted in its cooperating contact clips, the plunger 55 is now in position to strike but spaced from the tripping rod 53 upon the parting of the fusible element 25.

35 Contact member 10 which is similar in construction to contact member 11 except for the addition of the yoke shown in Figs. 3, 4 and 5, is then inserted in the hooks of the bent member 50, and swung against the bias of 40 the spring 48 until it is latched in a substantially vertical auxiliary position, where it is held by the action of the hook 51 of tripping rod 53 dropping over the upper portion of bent member 50, as shown in Figure 2.

45 It is now apparent that the parting of fusible element 25 due to any cause, as excessive current therethrough, will release the plunger 55, the latter moving upward under the bias of the spring 58. The impact of the 50 plunger 55 rotates the tripping rod 53 in its bearing 52, raising the hook 51 and in this manner disengaging the hook 51 from the bent member 50. The latter member then rotates the entire lower contact assembly including the contact clip 49 of the contact member 10 about the pivots 72. Since the contact member 10 is fixed in position by the contact clip 49 and the pins 38 engaging the hooks 50, the contact member is swung under the bias of the spring 48 from the vertical auxiliary position shown in Figures 1 and 2, to the circuit closing position shown in Figure 13.

The movement of the contact member 10 60 from the auxiliary position to the circuit

closing position is definitely guided between the parallel bars 67 to engage the contact 41 with the contact clip 86. The latch assembly above described prevents the passage of the contact 41 through the clip 86, and the impact due to the latching action is absorbed by the resilient design of the bent guiding bar member 67. 70

Upon the completion of the movement of contact member 10 from the vertical auxiliary position to the circuit closing position, the spring biased plunger 55 similarly attached to contact member 10 is in position to engage tripping rod 44 through the yoke 45 assembled on the tripping plunger of said 80 contact member 10.

The contact member 12 is adapted to be supported in a vertical auxiliary position in the same manner as that described with reference to contact member 10, and is thus adapted for 85 movement from the auxiliary position to the circuit closing position upon the parting of the fusible element of contact member 10. In this case the motion is transferred through the tripping rod 44 to unlatch the contact member 90 95 100 12.

Obviously any number of fusible contact members may be used through the addition of a tripping rod, a cooperating tripping plunger, and a cooperating contact clip support 95 for each additional contact member. However, actual experience indicates that more than two reclosures are seldom required, and that one reclosure will restore service in about eighty percent of the faults occurring 100 on overhead lines.

The device here disclosed operates in a very much shorter time than any with which we are familiar, due to the novel method employed in supporting the auxiliary contact members in a position without the circuit, and the new method of supporting the lower contacts of the contact members in the cooperating clips, so that no motion of the lower contacts is required with reference to 110 the cooperating clips. 105

It will be noted that provision has been made for entirely closing the upper end of the contact members, as it is very undesirable to expel the flame due to the action of a fuse 115 in an upward direction toward apparatus or live conductors. The flame attending the blowing of a fuse, especially one of the expulsion type, is highly conducting, and devices arranged for expelling flame in an upward direction toward line conductors often produce disastrous short circuits. 120

The positive means for guiding the movable contact members is also new, and makes possible a fuse-changing device for the higher voltages which necessarily require longer fuse tubes. 125

The action of this device, while very simple and positive, is substantially free from impact, due to the novel design of the mem- 130

bers supporting the auxiliary contact clips, and this consideration makes possible a very high speed circuit-reclosing device. Obviously the speed of the auxiliary contact members may be varied through a change in the characteristics of the spring 48; also the elapsed time for reclosure may be controlled by varying the length of the guide bars 67.

A further consideration contributing to the speed of operation of the device is the novel arrangement of parts which makes unnecessary the removal of the affected contact member from its position in the circuit to initiate the operation of the auxiliary contact members.

From the foregoing description taken in connection with the accompanying drawings, it will be apparent to those skilled in the art that we provide a novel and improved automatic fuse-changer for the purpose described.

What we claim as our invention is:

1. A repeating fuse adapted for installation in a circuit, comprising in combination insulating means supporting a fixed fuse-containing tube of insulating material and a plurality of movable fuse-containing tubes of insulating material, means for latching said movable tubes in a normal position out of the circuit, springs biasing said movable tubes to an operating position in the circuit, and unlatching means for said movable tubes including a fusible element under tension and means biased thereby, whereby the rupturing of the fuse in the said circuit effects the sequential actuation of the said movable tubes from said normal position to said operating position.

2. In a fused disconnecting device adapted for installation in a circuit, a pair of insulators supporting a fixed fuse-containing tube of insulating material and a plurality of movable fuse-containing tubes of insulating material, a base supporting said insulators, means for latching said movable tubes in a normal position out of said circuit, springs biasing said movable tubes to an operating position in said circuit, unlatching means for said movable tubes including a fuse under tension and a spring biased thereby, whereby the rupturing of said fuse in the said circuit permits the sequential actuation of the said movable tubes from said normal position to said operating position, and means including substantially parallel metallic contact-carrying bars for guiding said movable tubes from said normal to said operating position.

3. In a fused disconnecting device adapted for installation in a circuit, a pair of insulators supporting a fixed fuse-containing tube of insulating material and a plurality of movable fuse-containing tubes of insulating material, a base supporting said insulators, means for latching said movable tubes in a normal position out of said circuit, springs

biasing said movable tubes to an operating position in said circuit, unlatching means for said movable tubes including a fusible element under tension and a spring biased thereby, whereby the rupturing of the fuse in the said circuit permits the sequential actuation of the said movable tubes from said normal position to said operating position, and impact absorbing means including an arcuate resilient contact-carrying member.

4. In a circuit disconnecting device, in combination, fuse-containing contact members swingably disposed for movement in a direction toward cooperating contact members to close the circuit through a fusible element within said contact members, a trip mechanism including a spring-biased plunger forming one terminal of said fusible element, and means including a spring biasing said contact members for controlling the speed of movement of said contact members to the said cooperating contacts.

5. In a circuit disconnecting device, in combination, a pair of insulators supporting a plurality of fuse-containing tubes of insulating material having contacts adjacent the ends thereof, one of the said tubes being fixed in cooperating contacts in the circuit, and the remainder of said tubes swingably movable to cooperating contacts, means for latching said movable tubes in a normal position without the circuit, springs biasing said movable tubes to said cooperating contacts in said circuit, unlatching means adjacent the one end of said movable tubes including a spring-pressed movable plunger forming a terminal for one end of said fuse, and a cap for closing the other end of said movable tubes.

6. In a circuit disconnecting device, in combination, spring-pressed contact members swingably movable to cooperating contacts to close the circuit through a fusible element, and means including substantially parallel metallic guiding bars supporting said cooperating contacts for controlling the elapsed time for the movement of said contact members to engagement with the said cooperating contacts.

7. In a circuit disconnecting device, in combination, spring-biased contact members swingably movable to cooperating contacts to close the circuit through a fusible element, said contact members comprising a tube of insulating material having an upper contact and a lower contact adjacent the ends thereof, a fusible element within said tube connecting said contacts, a stationary contact for cooperating with said upper contact, and a hingedly fixed contact for cooperating with said lower contact, whereby the said tubes may be swingably urged for the engagement of the contacts mounted thereon with said cooperating contacts without motion of said

lower contact with respect to said hingedly fixed contact.

8. A circuit disconnecting device comprising, in combination, a support for a plurality of tubes of insulating material having an upper contact and a lower contact adjacent the ends thereof, a fusible element within said tube connecting said contacts, stationary upper contact clips for cooperating with said upper contacts, hingedly mounted lower contact clips for cooperating with said lower contacts, and means including a spring for urging said tubes to engage said upper contacts with said stationary contact clips, and means including a pair of hooks and a cooperating pivot adapted for rotation in said hooks for manually removing said tubes from said support.

9. In a repeating fuse, a plurality of pivoted fuse-containing tubes of insulating material having contacts adjacent the ends thereof, a spring biasing certain of said tubes to fixed cooperating contact clips for closing a circuit, a latch restraining the movement of certain of said tubes, and unlatching means including a spring-pressed plunger and a fuse connected to said plunger and restraining the movement of said plunger.

10. A circuit switching device comprising, in combination, a plurality of upstanding contact members, said contact members comprising tubes of insulating material having an upper contact and a lower contact adjacent the ends thereof, a fusible element within said tubes connecting said contacts; stationary resilient upper contact clips for cooperating with said upper contacts, hinged supports for certain lower contact clips for cooperating with certain of said lower contacts, a spring rigidly fixed to said hinged support biasing said contact member to engage said upper contact clips to close the circuit through said fusible element, means including a hook cooperating with said hinged support for latching certain of said contact members in an upstanding position, and unlatching means adjacent the lower end of said contact members including a spring-pressed movable plunger forming a terminal for one end of said fusible element.

11. A circuit switching device, having, in combination, a first removably fixed contact member comprising a tube of insulating material having an upper contact and a lower contact adjacent the ends thereof for cooperating with fixed contact clips to close the circuit through a fusible element extending through said tube and connecting the said contacts, a metallic cap adapted for attaching to the upper end of said first contact member for entirely closing the opening at the upper end of said tube and forming an upper terminal for said fusible element, a hollow spring-biased plunger having laterally extending pins adapted for reciprocatory move-

ment and guided in its reciprocations by a slotted metallic housing rigidly fixed adjacent the lower contact of said tube, a metallic cap adapted for attaching to one end of said plunger forming a lower terminal for said fusible element; a second contact member comprising a tube of insulating material having an upper contact and a lower contact adjacent the ends thereof, a lower contact clip for cooperating with said lower contact supported by a hinge, a spring fixed to said hinge biasing said contact member to engage a resilient cooperating contact to close said circuit through a fusible element contained in said second contact member, latching means for said second contact member including a U-shaped rod having a hook on one arm of the U for engaging said hinge and restraining the movement of the second contact member, a hinged support for said U-shaped rod and means for supporting the other arm of said U-shaped rod in position to engage said movable plunger mounted on said first tube whereby the said second contact member is actuated to close the circuit through the fusible element contained therein upon the passage of an excess current through the fusible element in said first contact member to restore the continuity of said circuit without movement of said first contact member with respect to said fixed contact clips.

12. In an automatic fuse-changer, comprising support and a plurality of fuse-containing insulating tubes having contacts adjacent the ends thereof, a fusible element connecting said contacts, means including a spring-biased movable metallic plunger fixed to said insulating tubes forming one terminal of said fusible element for exerting tension on said fusible element, and a latch operable by said plunger for latching said tubes in a definite position on said support, whereby a substantially fixed length of fusible element is required to latch said tube in said definite position.

In testimony whereof we affix our signatures.

RALPH R. PITTMAN. 115
CARROLL H. WALSH.
